[57] CLAIM

The ornamental design for an instrument for inguinal hernia surgery, as shown and described.

DESCRIPTION

FIG. 1 is a perspective view from above of an instrument for inguinal hernia surgery of this invention; FIG. 2 is a perspective view from below of FIG. 1; FIG. 3 is a left side elevational of FIG. 1, the right side elevational view not being shown as it is a mirror image thereof;

FIG. 4 is a front elevational view of FIG. 1;

FIG. 5 is a rear elevational view of FIG. 1;

FIG. 6 is a top plan view of FIG. 1; and,

FIG. 7 is a bottom plan view of FIG. 1.

The broken line showing of the hand in FIGS. 1 and 2 is for illustrative purposes only and forms no part of the claimed design.
